Letters Patent

The Schedule referred to in these Letters Patent, and making part of the same containing a description in the words of the said Benjamin Redhuffer and William Redhuffer themselves of their improvement in comb-making;

To all to whom these presents shall come: We do acknowledge that we Benjamin and William Redhuffer of Penn Township in the County of Philadelphia and State of Pennsylvania have invented a new and useful improvement in Comb-making - Solved a getting out and quilling Machine and that the following is a full and exact description of the construction and operation of the said Machine as invented by us.

The said Machine consists of several scrapers or cutters of different sizes, these scrapers can be made of cast steel or wrought from the cold by cutting teeth in them, or they can be made with knives or scrapers set round in a circle or cylinder with the concavity in them so as to produce the quills or ruffles, or the pieces - The plane scraper will do for all sizes if it is made about twelve inches long. The quilling scrapers, these must be made to every size, that is, in width for example, a piece that is to have one and a half teeth cut in it and the quills $\frac{1}{4}$ of an inch each, therefore the quilling scraper must be ten inches wide and the space between the quills must one inch and a half and so on to any size.

The quilling scraper may be used in a duplicate ratio on the same side of the travelling table, neatly adjusted on the same side. See the travelling plate first. C.C. - The plane into which the uprights are fast. B.B. with the sliding Boxes C.C. The rods A.A. are fastened to them with threads cut on the ends of them to admit the small nuts, a.a. so that the Boxes C.C. which holds the side of the receding scraper B. which can be raised or lowered by the screw A.A. the saw K.K. is fastened to the ends of the scraper B. to regulate the width. P. the pin is fastened to the side of the receding scraper B. with the small nut V. & the

travelling table or sliding plane working on the grooves U.L. At A the uprights to support the axle I. O.O the arms to support the roller R. The arms A is fastened to the spring F. with the chain m. which passes the roller R. on the moving plane B which is pushed forward and passes under the roller R. which keeps the piece level and prevents it from faring. (Plate 2.)

fig. 10. the moving plane fig 11. the upright fig 10 the roller and its frame fig. 9. The pulley Fig 8. O the axle. fig 7 the axle cylinder fig 5. The plain scroiling scraper fig 4. The quilling or concave scraper fig 3. The axle fig 2. The saws Fig 1. 1. will show the shapes of the knobs or cones pass which can be set around an axle or cylinder any number of them may be used to form one like fig 4. The plain scraper can be made the same. It is difficult to state in the above that the quilling and plain scroiling scraper is so constructed as to slide on and off the axle. so that the same axle may do for any size quiller. See the analytical drawing plate 2nd fig. 3. 4. 5. 7. There may be two or more of the quilling scrapers used on the axle at once if the workmen can attend to them.

The diameter of the revolving cylinders or scrapers may be from two to three inches.
